CLAIM

The ornamental design for an earring, as shown and described.

DESCRIPTION

FIG. 1 is a front, right-side, top perspective view of an earring, showing the new design;
FIG. 2 is a front elevational view thereof, the rear elevational view (not provided) being a mirror image thereof;
FIG. 3 is a left-side elevational view thereof;
FIG. 4 is a right-side elevational view thereof;
FIG. 5 is a top plan view thereof; and,
FIG. 6 is a bottom plan view thereof.
The broken lines depict parts of the earring that form no part of the claimed design.

1 Claim, 6 Drawing Sheets
